UNITED STATES PATENT OFFICE.

HARRY A. LAYCOCK, OF SCHENECTADY, NEW YORK, ASSIGNOR TO GENERAL ELECTRIC COMPANY, A CORPORATION OF NEW YORK

CONTACT-MAKING VOLTMETER.

1,119,616.

Specification of Letters Patent.

Patented Dec. 1, 1914.

Application filed December 11, 1913. Serial No. 806,067.

To all whom it may concern:

Be it known that I, HARRY A. LAYCOCK, a citizen of the United States, residing at Schenectady, county of Schenectady, State of New York, have invented certain new and useful Improvements in Contact-Making Voltmeters, of which the following is a specification.

My invention relates to contact-making 10 voltmeters, and more especially to an auxiliary switch provided in connection therewith as a protective device.

In the use of motor driven feeder regulators of the induction type, the operations 15 of the motor are controlled by means of a special form of relay commonly known as a contact making voltmeter. Variations in voltage on the feeders cause the voltmeter to close one or the other of two circuits and 20 thereby rotate the motor drive, and hence the induction regulator, in one direction or the other, so as to bring the voltage back to the desired value. In case the energizing circuit of the voltmeter relay is broken, or 25 in case the voltage on the feeder is temporarily interrupted, the voltmeter will so act as to cause the induction regulator to move to that position which would normally cause a maximum increase in voltage. When normal 30 voltage is again supplied, it is instantly boosted by the regulator as much as possible, and before the voltmeter and motor can operate to move the regulator into the maximum lowering position and thereby reduce 35 the voltage, considerable damage may result.

The object of my invention is to so construct a contact making voltmeter that in case of accident or temporary interruption 40 of the voltage, the voltmeter will automatically operate to cause the regulator to move to the maximum lowering position and on the resumption of normal conditions, will again perform its usual functions. I accomplish this object by means of additional contacts operated by the same solenoid which operates the usual contacts.

In the accompanying drawing, the single 45 figure is a diagrammatic view showing the construction of my voltmeter and the con-

nections between it and an induction regulator.

The feeders 1 are shown as connected to an induction regulator 2 of the usual construction which is operated by a motor 3. 55 The movements of the motor are controlled by my contact making voltmeter 10 having a solenoid core 11 operated by either one or both of the coils 12 or 13. Energy for the coil 12 is obtained from the current transformer 14 connected to one of the feeders, while that for the coil 13 is obtained from the potential transformer 15 also connected to the feeders. The coil 13 operates the voltmeter by raising and lowering the core 11 60 in response to variations of voltage on the feeders, while the coil 12 is used to oppose the coil 13 and compensate for line drop, means being provided to interrupt the circuit of either coil. At its upper end the core 11 is linked to a pivoted arm 16 to which is connected a spring 17 so designed as to aid in balancing the weight of the core when the desired voltage is obtained on the feeders. On the pivoted arm 16 I provide contact points 18 which in their movements touch one or the other of the adjustable points 19 and 20 which are flexibly supported by springs 19' and 20'. Power for driving the motor 3 is supplied from mains 30, 70 and between the motor and the mains is inserted a reversing switch 31 operated by solenoids 32 and 33. The oscillating arm 16 is connected with one side of the source of supply 30, and the common terminal of the 75 solenoids 32 and 33 is connected to the other side of said source. Movement of the pivoted arm 16 in one direction or the other closes the appropriate circuit to operate the reversing switch 31. Evidently, the switch 80 31 could be omitted and its work done by the arm 16, if desired.

It will be understood that the construction so far described is well known, and only shown to aid in understanding my invention. 90

Near the lower end of the core 11 of my voltmeter I provide a spring contact arm 40 electrically connected with the contact 19. On this arm are contacts 41 which move be- 100

tween adjustable contact points 42 and 43. I also provide an adjusting screw 44 for setting the spring arm 40 in the desired position. Suitable insulations 45 separates the contact spring 40 from the solenoid core 11. The upper contact 42 is connected with the solenoid 33, while the lower contact 43 is connected with the contact point 20 and with the solenoid 32.

10 The parts of my voltmeter are so designed and adjusted that a drop of approximately 25% in voltage will allow the core 11 to drop against the spring arm 40 and thereby close a circuit between the contact points 41 and 42. It will be understood that this circuit by energizing the solenoid 32 moves the reversing switch so as to cause the motor 3 to be driven in the appropriate direction to move the regulator 2 to the maximum lowering position. In normal operation the arm 16 floats between the contacts 19 and 20, but small variations in voltage will cause the voltmeter to close a circuit between the oscillating arm 16 and either of the points 19 and 20, and thereby energize the solenoids 33 and 32, respectively, to move the regulator to the boosting and lowering positions, respectively. That is to say, a drop in voltage below normal allows the core 11 to drop 30 slightly and bring the point 18 against the contact 19, thus energizing the solenoid 33. Similarly, an increase in voltage above normal raises the core 11 and closes the circuit of the solenoid 32. Energization of the solenoid 33 moves the switch 31 so as to cause the motor to turn the regulator toward the boosting position and vice-versa. Movement of the arm 16 sufficient to cause the contacts 18 to close one or the other of the 35 circuits is not sufficient to open the normally closed circuit through the contact points 41 and 42, but when an abnormal variation in voltage occurs the spring 19 will bend and allow the core to drop against the spring 40. Evidently, if the spring 40 and the contacts 45 42 and 43 are omitted, an interruption of or excessive drop in voltage will close the circuit to energize the solenoid 33 and thereby cause the regulator to be moved to the maximum boosting position. By my construction I have, therefore, provided a device that will 50 interchange the control circuit leading to one of the fixed contact points and thereby automatically move the regulator to a maximum lowering position whenever there is a failure of voltage on the feeders or whenever the connections between the feeder and the voltmeter are broken. This will prevent the voltmeter from causing the regulator to move to the maximum boosting position as it would otherwise do without the provisions of such an auxiliary switch, and will thereby prevent harmful increases in voltage on the

feeders. Further, the operation of my auxiliary switch is automatic, and upon a re-establishment of normal conditions on the feeders the voltmeter will again operate to control the regulator in the desired manner without any attention from an operator.

I conceive that variations and modifications of the exact arrangement which I have herein shown might be made, and I, therefore, do not wish to be limited to this exact arrangement, but seek to cover in the appended claims all such modifications and variations as come within the scope and spirit of my invention.

What I claim as new and desire to secure by Letters Patent of the United States is:

1. In a contact making voltmeter, a solenoid having a core operating a contactor and means associated with said core, operable when the solenoid is deenergized, to reverse the normal action of the contactor obtained by a decrease of voltage.
2. In a contact making voltmeter, a contactor, fixed contact points associated therewith, circuits leading therefrom, and means, normally unaffected, responsive to an abnormal variation in voltage to interchange the circuit leading to one of said points.
3. In a contact making voltmeter, a contactor, fixed contact points associated therewith, circuits leading therefrom, and means, normally unaffected, responsive to an abnormal decrease in voltage to interchange the circuit leading to one of said points.
4. In a contact making voltmeter, a solenoid, a floating core connected to a pivoted arm, contacts controlled by said arm, and means, normally unaffected, operated by an abnormal movement of said core to reverse the connections made by the simultaneous movement of said arm.
5. In a contact making voltmeter, a contactor responsive to voltage variations, closing alternate circuits, and means normally unaffected, operative upon an abnormal variation of voltage in one direction to reverse the circuit connection simultaneously made by the contactor.
6. In a contact making voltmeter, a contactor responsive to voltage variations, closing alternate circuits, and means, normally unaffected, operative upon an abnormal decrease of voltage to reverse the circuit connection simultaneously made by the contactor.
7. In a contact making voltmeter, a contactor arm pivoted intermediate its length, contact points co-operating with said arm near one end thereof, and means, normally unaffected, responsive to an abnormal movement of the other end of said arm to interchange the circuit connection to one of said contact points.

8. In a contact making voltmeter, a contactor normally floating between relatively fixed contact points, a solenoid for supporting said contactor and a contact spring operated by said contactor for interchanging the circuit connection to one of said points when the solenoid is deenergized.

In witness whereof, I have hereunto set my hand this 10th day of December, 1913.

HARRY A. LAYCOCK.
